DESIGN FOR A WASHING MACHINE CABINET

Amos E. Northup, Royal Oak, Mich., assignor to
Bendix Home Appliances, Inc., Detroit, Mich.,
a corporation of Delaware

Application December 9, 1936, Serial No. 66,393

Term of patent 14 years

To all whom it may concern:

Be it known that I, Amos E. Northup, a citizen of the United States, residing at Royal Oak, in the county of Oakland and State of Michigan, have invented a new, original, and ornamental Design for Washing Machine Cabinets, of which the following is a specification, reference being had to the accompanying drawing forming part thereof,

Figure 1 is a perspective front view of the washing machine cabinet showing my new design.

Figure 2 is a perspective rear view thereof on a slightly smaller scale.

I claim:

The ornamental design for a washing machine cabinet substantially as shown and described.

AMOS E. NORTHUP.
